CLAIM

The ornamental design for a feminine hygiene pad, as shown and described.

DESCRIPTION

FIG. 1 is a front elevational view of a feminine hygiene pad showing my new design;

FIG. 2 is a top plan view thereof;

FIG. 3 is a side view thereof;

FIG. 4 is an end view thereof; and,

FIG. 5 is a bottom view thereof.

The broken line in the drawing views represents unclaimed subject matters and form no part of the claimed design.

The applied stipple shading on the wing perimeter represents a color contrast.
